His Attorney.

UNITED STATES PATENT OFFICE.

ARTHUR D. AVERY, OF LOS ANGELES, CALIFORNIA.

GALLEY DEVICE.

1,380,516.

Specification of Letters Patent. Patented June 7, 1921.

Application filed July 24, 1920. Serial No. 398,724.

To all whom it may concern:

Be it known that I, ARTHUR D. AVERY, a citizen of the United States, residing at Los Angeles, in the county of Los Angeles and 5 State of California, have invented new and useful Improvements in Galley Devices, of which the following is a specification.

This invention relates to a galley device and has for an object the provision of a 10 device which will coöperate with a printer's galley whereby any type within said galley may be held in absolutely uniform and rigid alinement. It has for a further object the provision of a device which will give easy 15 access to the form upon said galley for altering or justifying said form as well as providing a convenient method of rapidly and accurately giving a uniform squeeze to the form. Another object is to prevent the 20 material within the galley from being bent or twisted when the forms are locked.

In practising the invention I provide a device which is utilized in combination with the ordinary form of printer's galley, which 25 galley may be provided with a plurality of transverse perforations extending along the longitudinal parallel upstanding side edges of said galley, and which device consists in a rod having eccentric end portions which 30 coöperate with the perforations. A tube rectangular in cross-section surrounds a portion of said rod and a handle means is likewise attached near one end of said rod. A yielding means such as a spring is interposed between one end of the rectangular bar and the handle means. The eccentric end portions of the rod are of sufficient length so that by compressing the yielding means an eccentric end portion may be readily 35 removed from one of the perforations and the entire bar lifted from the galley itself. A rotation of the rod when confined within the perforations located in the side walls of the galley will cause the rod to 40 travel forwardly or backwardly, as the case may be. It is intended that the rod should have such an eccentric relation that moving the same will cause the device to travel about a pica. Obviously if type or other form is 45 now within the galley, moving the galley device adjacent an end portion of said form,

and then rotating the device will cause it to squeeze against the form and hold said form in rigid alinement. It is therefore obvious that any altering or justifying of the form 55 may be readily made simply by releasing the galley device. It is to be understood, of course, that the opposite ends of the galley device are to be inserted in perforations located in the wall members of the galley 60 which are directly opposite one another.

Many of the devices on the market today used in justifying forms depend for their action upon squeezing the side walls of the galley or in having an edge of the galley 65 tray movable by means of screws or other suitable means. However, great difficulty is experienced with the devices now on the market in making a perfect form. In fact, an analysis of the delays and trouble between the setting of a type and its final acceptance on the press leads in nine cases out of ten direct to the galley job. The reason for the imperfect make-up may be due to a variety of causes, such as the linotype 75 slugs are not run true; cuts of all sizes and shapes are inserted in the form; the furniture may be warped, uneven or out of alinement; imperfect leads, slugs and rules; the squeezing, by the hand, is not sufficient to 80 secure a perfect, compact job, that will always line up or will always lift on the stone; a variety of opinions among different compositors as to allowances and measurements; a lack of means of proving a job until it is 85 tied up, and a disposition on the part of some compositors, if justifications are necessary, to let the stone-man do it; and a lack of mechanical means of determining accurately these conditions which effect perfect justification. 90

The invention has for further objects the provision of an improved galley device which will be superior in point of relative simplicity and inexpensiveness, taken in 95 conjunction with utility, durability and general efficiency and serviceability.

With the above and other objects in view, the invention consists in the novel and useful provision, formation, construction, combination, association, inter-relation of parts, members and features, all as disclosed in the 100

accompanying drawing, described in the following specification, and finally pointed out in claims.

In the drawing:

5 Figure 1 is a perspective view of a galley utilizing the improved galley device for justifying a form;

Fig. 2 is a fragmentary perspective view of an improved galley device;

10 Fig. 3 is an end view of the galley device;

Fig. 4 is a fragmentary perspective view of an attachment used in connection with the galley in place of boring holes upon 15 standing side walls of the galley; and,

Fig. 5 is a plan view of the attachment used in connection with the galley, certain parts being shown in section.

Corresponding parts in all the figures are 20 designated by the same reference characters.

Referring with particularity to the drawing, A designates a galley, B a galley device, C an accessory attachment for the galley, and D a form within the galley, all of 25 which elements are used in practising one embodiment of the invention.

The galley A is of standard form, in that it is tray-like in formation having its opposite longitudinal parallel sides provided with 30 upstanding wall members 1 and 2, and an end member 3. One edge as 4 is open. The galley A may be made in a variety of sizes; in fact, the galleys supplied printers come in what might be called standard sizes, depending upon the transverse width of the same.

The galley device B comprises in the main a rod 5 having eccentric end portions 6 and 7, which really comprise projections formed 40 at the ends of the rod 5 and off center of same as the term indicates. Surrounding a portion of the rod 5 is a bar 8 which is rectangular in cross section, as shown at 9. A lever or handle 10 is joined to and near one 45 end of the rod 5 as at 11. The free end of the lever or handle 10 is provided with a finger grip 12. It will be observed that a portion as 13 of the lever 10 is angularly bent, for reasons about to be explained. A 50 yielding means such as a spring 14 is interposed between an end 15 of the rectangular tube 8 and the lever 10. The yielding means 14 is helical in nature and surrounds the rod 5.

55 Referring to Fig. 1 it will be observed that the side walls 1 and 2 of the galley have been bored so as to provide a plurality of equally spaced transverse perforations 16. The perforations 16 are so bored that the perforations on opposite sides of each wall member 1 and 2 are directly opposite.

The galley device shown in Figs. 2 and 3 above described is then placed upon the galley A so that its eccentric end portions 6 and 7 may be placed within certain of the

perforations 16, as at 17 and 18. The perforations 16 as at 17 and 18, it will be observed, lie in the same plane. When the handle 10 is revolved from the dotted position shown to position shown by full lines, 70

it will be observed that the tube 8 is squeezed against an end of the form D in order to align the same or justify the form, as the case may be. Revolving the handle 10 back to the dotted line shown will cause the tube 75 8 surrounding the rod 5 to be refracted and release the form D. The handle 10 is bent as at 13 so that the fingers may readily grip the portion 12 when the handle 10 is in either one of the positions shown in Fig. 1.

80 As is standard practice the sides 1 and 2 of the galley A are provided with indications a so that the galley device may be always placed within the same perforations 16 for justifying the form. Ofttimes a form D will 85

bulge in the center, due to the unevenness of the linotype or the cuts, etc., and a releasing of the galley device by rotating the handle 10 will allow a piece of cardboard or other material to be inserted in the center of 90 the form D so that when the galley device is again locked in position, the bulge is removed from the form.

An accessory device C may be provided 95 so that boring holes in the sides 1 and 2 of the galley may be obviated. It has been stated above that the galley A may come in standard forms, and for this reason it is possible to provide accessory devices C of different lengths to correspond with the size 100 of the galley used. The accessory device C comprises a bar which is provided with a plurality of spaced transverse perforations b. An end of the accessory device C as at 19 is angularly disposed as at 20 and then 105 spacedly returned as at 21. The opposite end of the accessory device C is provided with a threaded extension 22 upon which a wing nut 23 turns.

Referring to Fig. 4, it will be seen that the 110 end 3 of the galley A is provided with perforations 24 located near the side walls 1 and 2. In fact, the perforations 24 are located a distance sufficient so that when the threaded extension 22 of the device C is passed 115 through the perforations the device C will be held adjacent the sides 1 and 2 respectively. The angularly disposed, spaced and returned end of the device C surrounds and cooperates with the free end as 25 of each 120 of the sides 1 and 2, as shown in Fig. 4. When the wing nut 23 is screwed upon the threaded extension 22 it will bear against the outside wall portion of the end wall 3 and tend to pull the device C. It will thus 125 be observed that the device C may be rigidly locked in position.

The operation is as follows:

Two of the accessory devices C are supplied with the galley device B and the ac- 130

cessory devices are arranged upon the galley adjacent the side walls thereof, as has been described. The galley device B is then so placed that one of its eccentric ends 5 passes within the perforations *b*. To this end when the devices C are supplied the eccentric end portions of the galley device B will have to be of such length that the eccentric end portions may readily be inserted 10 within the perforations or released therefrom. This might be done by having one of the eccentric end portions opposite, for instance, the lever, one-half the length of the other eccentric end portion. The 15 yielding means tends to force the eccentric end portion within the perforation so as to hold the galley device in position so that it will not escape from the perforation. If, as stated, the end opposite the handle means 20 is one-half the length of the opposite eccentric end portion, and an accessory device C is utilized, the galley device B will have to be of a length so that it may be released from the perforations *b*, when the accessory 25 device C is in position upon the galley. The longest eccentric portion may be inserted within the perforation *b* so that it extends through said perforation; then the other portion will be just even with the perforation 30 in the opposite accessory device C. Releasing the accessory device from its spring compression will force the shorter eccentric end portion within the perforation, and it will then be observed that each of the eccentric 35 end portions only extend half way through the perforations. Of course if the galley device has its opposite upstanding wall portions 1 and 2 bored a particular difference in the length of the eccentric portions 40 will not be necessary.

It is obvious that many changes and variations and modifications may be made in departure from the particular description, such as providing the accessory attachment 45 C with a longitudinal slot having one edge thereof serrated in place of providing a plurality of perforations *b*, and providing the eccentric end portions with knife-like projections to coöperate with the serrated 50 portions,—all without departing from or varying the conditions or requirements of the invention as shown.

Having thus disclosed my invention, I claim and desire to secure by Letters Patent: 55

1. In a galley device, the combination with a printer's galley, of a rotatable member adjustably and removably held between the side walls thereof in such a manner as to cause the body portion thereof to move 60 forward or backward when rotated, whereby any forms within the galley may be justified; said rotatable means having a part for engaging the form.

2. In a galley device, the combination 65 with a printer's galley having side walls

formed with perforations, of rotatable means adjustably and removably held between the side walls and within the perforations thereof; said rotatable means having a part for engaging a form within the galley 70 whereby upon a rotation of the galley device the form may be justified.

3. In a galley device, the combination with a printer's galley having side walls formed with perforations, of rotatable 75 means adjustably and removably held between the side walls and within the perforations thereof; said rotatable means having a part for engaging a form within the galley whereby upon a rotation of the galley device 80 the form may be justified; said galley device being provided with eccentric end portions.

4. In a galley device, the combination with a printer's galley and its longitudinal 85 side walls, of bars provided with perforations, removably coöperating with said walls and with perforations therein, and rotatable means detachably joining certain perforations in the bars whereby any forms within 90 the galley may be justified; said rotatable means having a part for engaging the form.

5. In a galley device, the combination with a printer's galley and its parallel walls, of bars provided with perforations, removably 95 associated therewith, and a rod provided with eccentric ends adapted to be received within the perforations of the bars, removably to secure the rod thereto, and whereby upon rotation of said rod it alters 100 its position so that any form within the galley may be given a uniform squeeze and maintained in rigid alinement; said rotatable means having a part for engaging the form. 105

6. In a galley device, the combination with a printer's galley provided with upstanding parallel side walls and an end wall, of a bar disposed adjacent each of said parallel side walls; each of said bars having a spacedly returned end portion for coöperating with an end of the upstanding parallel side walls of the galley, and means at the opposite ends of said bars coöperating with the end wall of the galley for 115 maintaining the bars in rigid position.

7. In a galley device, the combination with a printer's galley provided with upstanding parallel side walls and an end wall, of a bar disposed adjacent each of 120 said parallel side walls; each of said bars having a spacedly returned end portion for coöperating with an end of the upstanding parallel side walls of the galley, and means at the opposite ends of said bars coöperating 125 with the end wall of the galley for maintaining the bars in rigid position; said means comprising a threaded portion on the end of said bars passing through a perforation in the end wall of the galley, and 130

wing nuts upon the threaded portion for adjustment against the end wall.

8. In a galley device, the combination with a printer's galley provided with up-
5 standing parallel side walls and an end wall, of a bar disposed adjacent each of said parallel side walls; each of said bars having a spacedly returned end portion for coöperating with an end of the upstanding
10 parallel side walls of the galley, and means at the opposite ends of said bars coöperating with the end wall of the galley for maintaining the bars in rigid position; each of the bars being provided with spacedly
15 arranged transverse perforations, and means adjustably and removably coöperating with the said bars and the perforations therein, whereby any form within the galley may be justified; said last named means having
20 a part for engaging the form.

9. A galley device for use in combination with a printer's galley, comprising a rod having eccentric end portions, a tubular portion rectangular in cross section sur-
25 rounding said rod, a handle joined to the rod provided with eccentric end portions, and yielding means disposed between the handle and the tubular rod which is rect-
angular in cross section.
30 10. In a galley device, the combination with a printer's galley, of rotatable means adjustably and removably mounted between the side walls thereof, whereby any forms within the galley may be justified; said ro-
35 tatable means having a part for engaging the form; said part for engaging the form comprising a tube rectangular in cross section loosely surrounding said rotatable means.

- 40 11. In a galley device, the combination with a printer's galley having side walls formed with perforations, of rotatable means adjustably and removably held between the side walls and within the perforations
45 thercof; said rotatable means having a part for engaging a form within the galley

whereby upon a rotation of the galley de-
vice the form may be justified; said rota-
table means comprising a rod provided with
eccentric end portions.

50

12. In a galley device, the combination with a printer's galley having side walls formed with perforations, of rotatable means adjustably and removably held be-
55 tween the side walls and within the per-
forations thereof; said rotatable means hav-
ing a part for engaging a form within the galley
device the form may be justified; said ro-
tatable means comprising a rod provided 60
with eccentric end portions, and said part
for engaging the form comprising a tube
rectangular in cross section loosely sur-
rounding said rod.

55

13. In a galley device, the combination 65 with a printer's galley having side walls formed with perforations, of rotatable means adjustably and removably held be-
tween the side walls and within the per-
forations thereof; said rotatable means hav-
ing a part for engaging a form within the galley
device the form may be justified; said ro-
tatable means comprising a rod provided 70
with eccentric end portions, and said part
for engaging the form comprising a tube
rectangular in cross section loosely sur-
rounding said rod; handle means being
joined to said rod whereby the said rod
may be rotated, and yielding means inter-
posed between the handle and the tube
which is rectangular in cross section, where-
by the rotatable means may be prevented
from accidental detachment from the per-
forations.

75

In testimony whereof, I have signed my
name to this specification in the presence of
two subscribing witnesses.
